METHOD OF AND MACHINE FOR ASSEMBLING AND SEWING MOCCASIN TYPE SHOES

Fred Ashworth, Wenham, Mass., assignor to United Shoe Machinery Corporation, Flemington, N. J., a corporation of New Jersey

Application March 12, 1942, Serial No. 434,366

25 Claims.

(Cl. 112—60)

The present invention relates to improvements in methods and machines for sewing moccasin seams and is herein disclosed as embodied in a method and a machine particularly designed for use in uniting the side piece or vamp and the top piece or tongue of an imitation moccasin or moccasin type shoe. A machine for sewing moccasin seams of the same general nature formed by the method and machine of the present invention is illustrated and described in U. S. Letters Patent to the present inventor, No. 1,975,914 of October 9, 1934.

Present day commercial practice in moccasin type shoe making includes the steps of cutting out suitably shaped pieces of upper stock and preparing the pieces by beveling the edges so that they are assembled with the faces of the bevels in register. The pieces are secured together by cement and then sewed with the stitches passing through the bevel faces at the shoulders formed by the intersection of the bevel faces with the inner surfaces of the moccasin pieces. To enable the sewing operation to be performed on a commercial type shoe sewing machine and to prevent distorting the edges of the pieces operated upon when the stitches are tightened, the edges of the pieces are beveled at an angle which causes the outer surfaces of the pieces when assembled to form an acute angle. However, due to the shape in which the pieces are cut, the surfaces of the pieces remote from the sewed edges extend at a comparatively greater or obtuse angle with relation to each other, oftentimes approaching a relationship of approximately 180° along some portions of the completed upper. Thus while securing the pieces by cement, it is necessary to flex the pieces operated upon from the greater angular relationship remote from the meeting edges into the smaller angular relationship along the edges, the tenacity of the cement employed acting to retain the faces on the bevels in register against the forces resisting flexure in the pieces while sewing. To reduce these forces, the top piece frequently is pre-formed by a separate edge bending operation. The assembling and cementing operations are also surrounded by other practical difficulties which require careful workmanship, particularly when the moccasin pieces are not cut accurately to the correct shape. Also, due to irregular qualities of compressibility and flexibility in the materials employed for moccasins or moccasin type shoes, the registering faces on the bevels frequently are pulled apart or displaced from proper register

during sewing, in spite of careful assembling and cementing operations.

Due to the fact that the bevel edged pieces of a moccasin type shoe, when assembled with the bevel faces in contact, diverge along some portions of the completed upper at a greater angle with relation to each other than the angle formed at the meeting edges, as above pointed out, and also due to the fact that the extreme outer edges of the pieces along the bevel faces are extremely thin, it has heretofore been necessary to assemble the pieces and secure them temporarily with cement before they are presented to a shoe sewing machine of the type disclosed in the patent above referred to. Machines of the type disclosed in the patent are provided with an external work support having work engaging surfaces angularly disposed with relation to each other and extending in the line of feed and with a cooperating internal presser having corresponding work engaging surfaces. When the bevel edged top and vamp pieces of a moccasin type shoe are presented to such an external work support and internal presser without being previously assembled and cemented, it has been found to be impossible to bring the edges of the pieces at the outer edges of the bevel faces into register and maintain them in register while the seam is being inserted, displacement of one piece with relation to the other being occasioned by the stresses produced in the pieces resulting from flexure necessary to bring the bevel surfaces into contact, the resistance offered by the thin edges of the pieces as these edges are forced within the apex of the external work support being insufficient to bring the edges into register or maintain them in this position. As a result of the stresses in the pieces and the failure of the work support to properly guide the thin edges, one piece is displaced with relation to the other sufficiently to cause the seam to present an irregular appearance and often at some point along the seam to run entirely off of either the top piece or the vamp.

The objects of the present invention are to obviate the difficulties referred to and to provide a sewing machine in which the pieces of a moccasin or moccasin type shoe upper may be united progressively in a reliable and uniform manner without the necessity of performing separate assembling and cementing operations. A further object is to improve the methods of sewing moccasin seams so as to enable an operator to unite permanently the top and vamp pieces of a moccasin without the necessity of exercising as much care and at-

tention in guiding the pieces as have heretofore been required.

With the above and other objects in view, a feature of the present invention contemplates progressively assembling the bevel edged toe piece and vamp of a moccasin type shoe by guiding the bevel face of one piece independently of the bevel face of the other piece to bring the edges of the pieces into register progressively along said edges and progressively securing the assembled pieces while thus in register. By utilizing the bevel faces of the pieces, the positions to which the pieces are moved during the assembling operation are determined independently of the outer edges of the bevel faces and thus accurate register of the edges can be secured regardless of the thinness of the outer edges produced in beveling.

The present invention also contemplates the provision in a sewing machine operating progressively to unite the edges of the top and vamp pieces for a moccasin shoe upper in which there are provided an external work support and an internal presser having work engaging surfaces properly disposed to cause the moccasin pieces along the edges to be brought together, of a centering gage for preventing one moccasin piece from displacing the edge of the other moccasin piece in advance of the sewing point. As hereinafter illustrated, the centering gage consists of a fin extending between the edges on the moccasin pieces in advance of or opposite to the point of operation of the sewing instruments and preferably the gage is mounted within the apex of angularly disposed work engaging surfaces on the work support. The bevel faces of the pieces are engaged by the centering fin and the fin, in addition to preventing displacement of one piece by the other, acts as a guide to determine the position of each piece independently and locates each piece accurately, regardless of the thinness of the extreme outer edges. When mounted on the work support, the centering fin opposite the point of operation of the needle and awl enters a short distance only between the outer edges, stopping short of the seam line to avoid interference with the stitch formation.

To enable two moccasin pieces to be clamped securely within the apex of the angle on the work support, the presser of the present machine is provided with a divided tip, the parts of which are movable with relation to each other and which act on the pieces separately. According to this feature, the tip is actuated to urge one of the pieces towards the apex of the work support before the other piece of the moccasin is clamped. The side piece or vamp of the moccasin, due to its shape, is the most difficult to locate with its edges in accurate registration with those of the top piece and in the embodiment of this feature, that portion of the presser tip which engages the side piece or vamp of the moccasin is constructed to yield after engaging the work. Also to assist further in urging both moccasin pieces into the apex of the work support, the tip of the presser is roughened with projections extending parallel to the line of feed so as not to exert resistance during work feed.

The tongue or top piece of a moccasin is more nearly flat than the side piece or vamp and therefore is more easily manipulated during assembling and sewing operations. As a means for insuring that the top piece shall be held substantially flat so that it may be assembled with the vamp of a moccasin merely by moving the top

piece in its own plane as the operation progresses about the curved end of the top piece, a flat guiding plate is provided, according to a further feature of the invention, for supporting the top piece in a flattened condition throughout a substantial proportion of its area to cause all of the flexure required in bending both moccasin pieces from an acute angle along their edges towards an obtuse angle remote from their edges to be taken up by the vamp during sewing. To facilitate turning the top piece while sewing around the curved end, in the present form of this feature, the tip of the presser in advance only of the point of operation of the sewing instruments engages the top piece so that the oncoming portion of the edge on the top piece will be crowded into the apex of the work support more firmly than the outgoing sewed portion of the edge. Thus, as the curved toe end of the top piece is reached, the action of the presser tends to cause the top piece to turn more or less by itself. By so doing, the operator of the machine is able better to give his full attention to proper manipulation of the vamp and to lead the bevel face on the vamp more accurately into register with the bevel face on the top piece. The vamp of the moccasin is cut along its beveled edge with a concave contour. Accordingly, uniform engagement of the presser tip with the vamp along the seam line at both sides the point of operation of the sewing instrument is best suited to urge the vamp into the apex of the work support without crowding out the top piece.

Another feature of the invention relating to the method of uniting the pieces of a moccasin upper contemplates a mode of operation consisting in flexing the moccasin vamp while holding the top piece in flattened condition. This feature is of special advantage when sewing the pieces together and also in certain aspects is useful where other forms of fastenings are employed, whether the pieces are united progressively or in a single operation.

With the parts constructed and operated in the manner briefly described, not only is it possible to assemble and unite progressively in the same operation the vamp and top piece of a moccasin or moccasin type shoe upper, but certain features of the invention such as those relating to the divided tip on the presser are advantageous in use when sewing previously assembled and cemented moccasins according to present commercial practice. When sewing moccasin uppers not previously assembled or those not completely cemented, the edge guide fin ensures an accurate and uniform register of the bevel faces on the work pieces operated upon. With the present machine, a satisfactory seam may thus be sewed with the assurance that the moccasin pieces will be united uniformly in a preferred relationship.

These and other features of the invention consist in certain devices, combinations and arrangements of parts hereinafter described and claimed, the advantages of which will be obvious from the following description taken in connection with the accompanying drawings, in which Fig. 1 is a view in side elevation of a portion of the working mechanism for a machine embodying the several features of the invention; Fig. 2 is a sectional view on an enlarged scale of the work support and presser, together with a portion of a moccasin illustrating the manner of operation of the presser directly after work feed;

Fig. 3 is a similar view of the same parts illustrating the positions assumed when the work is clamped; Fig. 4 is a sectional plan view of the same parts in the positions of Fig. 3; Fig. 5 is a detail view in side elevation on a further enlarged scale of the presser tip; Fig. 6 is an end view of the work engaging surfaces on the presser tip; Fig. 7 is a bottom plan view of the tip; Fig. 8 is a detail view in plan looking from above the work support and presser tip illustrating the manner of operation of the parts while assembling and sewing the toe portion of a moccasin; Fig. 9 is a view in side elevation of the parts illustrated in Fig. 8; Fig. 10 is a view on a somewhat reduced scale indicating the relation of the moccasin pieces when the seam is partially completed; Fig. 11 is a detail front view of a portion of the presser supporting horn and its fulcrum pivot; Fig. 12 is a further enlarged view looking from the left side of the fulcrum pivot; and Fig. 13 is a detail view taken in section along the line 13—13 of Fig. 10, illustrating the usual angular relationship of the pieces in a moccasin after being secured together.

The illustrated machine, in its construction and mode of operation is similar, except as hereinafter described, to that of the Ashworth patent above referred to. The machine is equipped with a curved hook needle 2, a curved work penetrating and feeding awl 4, a work support 6, a horn 8 having a presser secured thereto, a rotary hook 10 which carries loops of needle thread over a locking thread case contained therein, and other stitch forming and thread handling devices of the usual form. The needle and awl are secured to carriers mounted in a bracket 12 forming a part of the machine frame to which the work support is clamped. The needle and awl carriers are actuated to cause the needle to enter the work from above, following the awl closely as it leaves the work at the opposite side. When the awl withdraws from the work, it is back fed the length of a stitch and again penetrates the work. The awl feeds the work with a step-by-step movement during successive sewing cycles. During feeding movement of the work, the pressure of the presser on the work is relieved and the awl and work move in the direction of feed to a position with the awl perforation in line with the needle. The work support is formed with a V-notch, the inner work engaging surfaces of which are disposed at an acute angle to each other. The presser has a similar acute angle shape and is formed as disclosed in United States Letters Patent No. 2,304,964, granted December 15, 1942, upon an application filed in the name of Francis R. Speight, with vertical notches spaced a stitch length apart in the work penetrating path of the awl and in line with the path of the needle, respectively. When the pressure on the work is relieved, the presser moves away from the needle and awl sufficiently to enable the awl to move freely from alignment with the first vertical notch in the presser to the second vertical notch, the notches being of substantially the same shape so that the same areas of the work about the needle are compressed by the presser after each feeding movement as were compressed about the awl.

The top piece and vamps of a moccasin type upper are indicated at 14 and 16 in Fig. 10 and are sewed together before the vamps are lasted or attached to a sole. In order to provide an easily lasted upper, the inner concave edge portion in-

dicated at 18 of the vamps is cut with a greater radius than the outer edge portion 20 of the top piece 14, so that when the edges are brought together, the shape of the completed upper will approximate more nearly the shape into which it is to be lasted. In most instances, the curvature of the flattened vamps is chosen to cause an obtuse angle 22 to be formed, as indicated in Fig. 13, with the top piece, particularly at the toe end where the greatest stretching and shaping ordinarily occur during lasting operations, although where the vamps is cut to include the heel end of the upper, it is usual, for purposes of economy in upper material, to cut the inner concave edge of the vamps with a radius somewhat less than the radius of curvature along the outer edge of the top piece. In such cases, when the edges of the top piece and vamps are brought into register, the surfaces of the pieces may extend at an angle of approximately 180°.

Where machines such as disclosed in the patents referred to are employed, the inner and outer edges of the vamps and top piece, which are to be united, are beveled at an angle approximating 30° so that when the faces 24 and 26 of the respective bevels are brought into register, the acute angle 28 will be 60° between the outer surfaces along the edges, the stitches passing through the inner shoulder along the bevels and intersecting the bevel faces. Before sewing the edges, it has heretofore been found necessary to fasten them temporarily together, due to the tendency of the edges to separate as a result of being flexed from an obtuse angular relationship remote from the edges into an acute angular relationship along the edges. For this purpose, the faces 24 and 26 of the top piece and vamps are temporarily united with cement in the positions at which they are intended to be sewed. Due to handling while being carried from one operating station to another, the pieces may become uncemented and displaced from each other so that before sewing operations can be started, the correct relative positions of the parts must be restored. The action of the presser in clamping the parts also tends to separate their beveled edges during sewing.

The machine of the patents is provided with a work support and a presser for clamping the moccasin pieces with their cemented bevel faces in the path of operation of the stitch forming devices. If the moccasin pieces 14 and 16 are displaced along their edges from each other or if the cement bond is of insufficient strength to hold the pieces together properly during sewing, the tendency is for the edge of the vamps to be forced into the apex of the work support 30 as the sewing operation approaches the portions 18 and 20 of greatest curvature along the edges of the pieces. When this occurs, the edge of the vamp 16 enters too far within the apex of the work support and the top piece 14 is crowded out of the apex, the thinness of the bevel edges affording insufficient strength to enable them to be guided accurately. This action may be so slight as to escape a casual inspection of the completed upper, but in extreme cases, the seam may run entirely off the top piece, the needle and awl passing between the meeting edges.

The machine of the present invention is so constructed and arranged that the separated bevel faces on the top and vamps pieces for a moccasin type shoe upper may be guided towards each other and united with a permanent uniform seam without the necessity of any preliminary shaping

or temporary cementing operations, the difficulties encountered in handling the temporarily cemented pieces thereby being eliminated. Furthermore, the sewing operation, in which the pieces are permanently united, being combined with the assembling operation, it is possible for the machine operator to give his full attention to proper location and direction of the pieces while being sewed, with the assurance that when correctly assembled, the relative positions will be retained. Thus there are beneficial results obtained from the use of the improved machine both in quality of finished work, as well as in reduction of the number of operations required. Also, a further improvement in uniform tightness of the joint between the exposed meeting edges along the registering bevel faces on the top and vamp pieces follows from the method of assembly employed in the machine, as will be described more fully.

In preparation for the present method of assembling the moccasin vamp and top pieces, the pieces are cut out and formed with bevels along their edges in the usual way and are presented in unattached relation to the machine with the starting ends of the bevel faces in alignment. When the machine begins to operate, the vamp 16 is forced by movement of the presser into the apex of the work support to crowd the meeting faces of the bevels on the pieces into register, rather than merely to clamp the temporarily cemented pieces in position as heretofore, the presser and the work support being constructed and arranged to accentuate the crowding action while enabling the operator to guide and control the pieces with little or no effort.

Another feature of the present method of assembling a moccasin upper, which contributes effectively to an improvement in ease of manipulation of the upper pieces during sewing and in quality of the product resulting, consists, in addition to utilizing the bevel faces of each piece independently to bring the edges into register, of crowding the edges of the pieces into the apex formed by the work engaging surfaces of the work support by clamping the pieces separately so that the clamping action on one piece will not tend to crowd the other piece out of the apex, thus rendering it possible to guide the pieces more effectively. As a means for still further assisting the guiding and manipulating operations, the top or tongue piece of the upper is held in substantially flattened condition at and in advance of the sewing point. As soon as the sewing operations are started, the leading end of the notch in the work support acts progressively to bring the beveled edges together along its work engaging surfaces which are disposed at an acute angle to each other, the outer surfaces of the pieces assuming positions at the same angle as that of the notch in the work support, both along and remote from the edges of the pieces, until the toe portion of the seam is reached. Until the toe portion is reached, the seam has insufficient curvature to produce any displacing effort between the moccasin pieces. As the bevel faces are brought into register about the toe portions of the seam, however, the pattern in which the pieces are cut tends to cause the outer surfaces remote from the edges to assume an obtuse angular relationship instead of acute angle positions, but the portions of the seam already sewn resist the change. In overcoming the resistance offered, the pieces themselves are flexed by the presser from the acute angle relationship indicated by the angle

28 of Fig. 13 into the obtuse relationship indicated by the angle 22.

As a result of holding the top piece in flattened condition at and in advance of the sewing point, all of the flexure required to bring the bevel faces on the pieces into register is taken up at the sewing point by the vamp. The relation of the pieces when the toe is reached is indicated in Fig. 10, the sewed portions diverging from an acute angle at the edges to an obtuse angle remote from the edges while the unsewed portions tend to hold their separated and flattened condition. While sewing the toe portion of the seam, the top piece is turned gradually within its own plane and the vamp is bent while being crowded by the presser into the apex of the V-notch in the work support. After leaving the work support, the sewed portions of the pieces are released from engagement by the presser so that the bent vamp tends to straighten out and the flattened top piece takes up the flexure released from the vamp, thus balancing the forces tending to bend the pieces along the seam line.

Not only is the top piece more easily manipulated while held in flattened condition, but the outer edges along the bevel faces of the pieces are brought together more tightly than in prior methods of sewing moccasin seams. Where the tongue has been pre-formed, according to prior methods, with an angular flange to assist in assembling operations, some of the natural resiliency in the top piece is lost so that there is a tendency for the top piece to take up all of the flexure required to bring the bevel faces on the pieces into register at the sewing point. For this reason, there is a greater tendency for the sewed edges to gap in a completed moccasin sewed according to prior methods.

To prevent the force of the presser while acting to crowd the edge of one moccasin piece into the apex of the work support from displacing the edge of the other piece, the illustrated machine is provided with a centering gage in the form of a fin 30 secured between two separable portions of the work support at the apex of the angle formed by the work engaging surfaces. At the leading edge of the fin 30 is an enlarged area 32 to insure entrance between the bevel faces on the pieces with the greatest possible degree of curvature along the toe. Opposite the point of sewing operations, the fin 30 extends in the direction of feed sufficiently to enter a short distance between the edges of the moccasin pieces, the exposed edge 34 of the fin clearing the seam line so as not to interfere with the needle and awl. By this construction, the locations of the edges on the moccasin pieces are correctly maintained at all times.

For purposes of improving visibility and convenience in manipulation of the temporarily cemented moccasin pieces while being sewed, the top piece 14 is usually presented to the lower work engaging surface of the work support and the vamp to the uppermost work engaging surface, the vamp being narrower than the top piece, thus interfering to a less degree with the operator's line of vision. With the construction of the present machines, the separated moccasin pieces are intended to be presented in the same manner as previously.

The presser of the present machine has its work engaging surfaces disposed at the same angle as those within the notch in the work support and is provided with a divided tip, the upper section 36 of which acts with a yielding

pressure on the vamp at both sides of the paths of needle and awl to assist in securing the vamp in position while flexing the edge and crowding it into conformity with the angle of the work support against the centering fin at the apex of the angle. The other lower section 38 of the tip is provided with a surface having a raised portion 40 acting separately on the top piece of the moccasin at a location along the seam line with reference to the direction of feed in advance only of the needle and awl paths so that as the presser moves towards the work support in clamping the work, there is a tendency to urge the edge of the top piece along that portion which is entering the notch of the work support from the right more firmly into the apex of the work support than along the sewed portion of the top piece edge which is leaving the work support at the left. With such an arrangement, when the toe portion of the moccasin seam is reached, the clamping action of the presser foot causes a turning movement to be imparted to the top piece in the direction of the arrow 42 (Fig. 8) without requiring any special effort on the part of the operator, thus enabling the operator to give full attention to manipulation of the vamp.

The vamp engaging section 36 of the presser tip is of wedge shape at its forward work engaging end and is roughened with elongated projections 44 extending parallel to the line of feed for obtaining a better grip on the vamp to cause it to be urged more deeply into the apex of the work support when the presser clamps the work. Connecting the forward end of the presser tip section 36 is a semi-circular shank 40 slidingly mounted in the upper half of a round socket 48 in the horn and having at the end opposite its work engaging end a fully circular seat 46 against which the compression spring 50 acts. The socket 48 is arranged in the horn to enable the vamp engaging tip section 36 to slide in the direction of presser movement towards and from the work support. The spring 50 is retained within a passage at the upper end of the horn 8 in line with the socket and is held under compression by an adjustable set screw 52 threaded into the spring retaining passage.

The lower top piece engaging section 38 of the presser tip is cut away along its work engaging end to form the raised portion 40 which has on its work engaging face a series of elongated projections similar to those indicated at 44 on the vamp engaging section of the tip. The shank of the top piece engaging section 38 is of semi-circular shape fitting within the lower half of the socket 48 in the horn 8 and being secured rigidly within the socket by a clamp screw 54 passing through the side walls of the socket into the shank of the section 38. The fully circular end of the vamp engaging tip section 36 not only forms the seat 46 for the spring 50, but overlies the end of the section 38 to provide a limiting stop resisting the forward movement of the section 36 under the influence of the spring 50 (see Fig. 2). The two sections are so arranged that before the work is clamped during each sewing cycle, the vamp engaging section 36 projects towards the corresponding work engaging surface on the work support somewhat further than the top piece engaging section 38 to its corresponding work support surface. As the presser tip moves towards the work support, the section 36 first engages and crowds the vamp into the

5 apex (Fig. 2) and then yields against the pressure of the spring 50 until the section 38 crowds the top piece into the apex of the work support, both moccasin pieces thereafter being clamped (Fig. 3).

The means for supporting and holding the top piece of the moccasin upper in flattened condition both at the edge and remote from the edge to cause all the flexure at the sewing point required in bending the moccasin pieces from an acute angle along the edges towards an obtuse angle remote from the edges to be taken up by the vamp, consists of a plate 56 on the work support extending along the seam line in advance of the sewing point and beneath a substantial area of the top piece, as illustrated in Figs. 8 and 9. The presser tip acts with the plate to flatten the top piece at the same time or directly after the vamp is crowded into the apex of the work support during each sewing cycle. The top piece supporting plate extends only slightly beyond the sewing point in the direction of feed to enable the moccasin pieces to assume a relationship determined by the forces set up in the pieces during sewing, the sewed portion of the top piece being unsupported after leaving the plate 56. After the top piece leaves the supporting plate, the flexed vamp tends to straighten out and the flattened top piece takes up the flexure released from the vamp until the resilient forces within the pieces substantially balance each other. When this occurs, the positions of the pieces will enable the seam to assume smoothly progressing changes in curvature around the toe portion without irregularities ordinarily resulting from inaccurate register of the bevel faces on the edges of the pieces and will produce a uniformly tight joint with a maximum possible pressure between the exposed edges of the pieces, tending to hold the edges together against the tendency to gape. The shape of the seam with the top piece held flat will conform more accurately to the configuration of the top piece and will cause the completed moccasin to have a better shape for lasting purposes than those moccasin uppers sewed by performing the top piece with an angular flange around its margin.

The mechanism for actuating the presser towards and from the work support during each sewing cycle is the same as employed in the machine of the patents above identified. This mechanism consists briefly of a link 58 connecting the horn 8 above its fulcrum with a floating lever 60, a link 62 connecting the lever 60 with a presser foot actuating spring 64, a presser foot lock 66 connected to the fulcrum of the floating lever 60 and actuated by a lever 68 engaging a cam on a sewing shaft 70 and a cam actuated lever 72 adjustably connected to the floating lever by a link 74. The arrangement is such that during each sewing cycle, the cam lever 72 causes the presser to be moved away from the work support while the work is being fed and the spring 64 causes the presser to reengage and clamp the work after the feeding movement has taken place. The force of the spring 64 ordinarily is sufficient to overcome the pressure of the spring 50 for the presser tip so that the action of the presser in urging the moccasin pieces into the apex of the notch in the work support is yielding in its nature. It is possible, however, to so adjust the set screw 52 that the spring 50 will not be compressed fully when the presser yieldingly engages the vamp, in which case, it is

necessary, in order that the top piece will be clamped securely, to adjust the timing of the lock 66 and the connection between the link 74 along a slot 76 in the lever 72 so that after the fulcrum for the floating lever is locked in each sewing cycle, there will be a positive movement imparted to the horn 8.

The fulcrum for the horn 8 consists of an eccentric pivot 77, the eccentric portion of which is adjustably secured by a set screw 78 within a bracket 80 fast on the machine frame to insure that the section 36 of the presser will engage the moccasin vamp before the presser section 38 engages the top piece. The horn is formed with spaced bearing portions, as indicated in Fig. 11, surrounding the ends of the pivot 77, so that when the pivot is rotated, it will cause the horn to be raised or lowered with respect to the work support.

The nature and scope of the invention having been indicated, and an embodiment of the invention having been specifically described, what is claimed is:

1. In a machine for bringing together progressively the edges of the bevel edged top and vamp pieces of a moccasin type shoe upper and simultaneously inserting a permanent seam along the edges, the combination with a work support having work engaging surfaces disposed at an angle with relation to each other and extending in the direction of feed, a presser acting on the pieces to crowd the pieces into the apex formed by the angularly disposed work engaging surfaces of the work support, and stitch forming devices including a work penetrating instrument operating across the apex of the work support, of guiding means on the work support arranged to engage the bevel faces of the pieces to bring the edges progressively into register with the bevel faces in the path of the stitch forming devices.

2. In a machine for bringing together progressively the edges of the bevel edged top and vamp pieces of a moccasin type shoe upper and simultaneously inserting a permanent seam along the edges, the combination with a work support having work engaging surfaces disposed at an angle with relation to each other and extending in the direction of feed, a presser acting on the pieces to crowd the pieces into the apex formed by the angularly disposed work engaging surfaces of the work support, and stitch forming devices including a work penetrating instrument operating across the apex of the work support, of a gage at the apex of the work support arranged to extend between the bevel faces of the pieces and to bring the edges of the pieces into register progressively with the bevel faces in the path of the stitch forming devices.

3. In a machine for bringing together progressively the edges of the bevel edged top and vamp pieces of a moccasin type shoe upper and simultaneously inserting a permanent seam along the edges, the combination with stitch forming devices including a work penetrating instrument, and a work support having work engaging surfaces disposed at an angle with relation to each other and extending in the direction of feed and a presser acting on the pieces to crowd the edges into the apex formed by the angularly disposed work engaging surfaces of the work support with the bevel faces registering in the path of operation of the stitch forming devices, of a centering fin extending between the edges on the moccasin pieces in advance of the point of operation of the work penetrating instrument, and a tip on the

presser constructed and actuated to clamp the moccasin pieces separately during each sewing cycle.

4. In a machine for bringing together progressively the edges of the bevel edged top and vamp pieces of a moccasin type shoe upper and simultaneously inserting a permanent seam along the edges, the combination with stitch forming devices including a work penetrating instrument, and a work support having work engaging surfaces disposed at an angle with relation to each other and extending in the direction of feed and a presser acting on the pieces to crowd the edges into the apex formed by the angularly disposed work engaging surfaces of the work support with the bevel faces registering in the path of operation of the stitch forming devices, of a centering fin on the work support extending in the direction of feed from the apex of the angularly disposed work engaging surfaces of the work support opposite the point of operation of the work penetrating instrument.

5. In a machine for bringing together progressively the edges of the bevel edged top and vamp pieces of a moccasin type shoe upper and simultaneously inserting a permanent seam along the edges, the combination with stitch forming devices including a work penetrating instrument, a work support having work engaging surfaces disposed at an angle with relation to each other and extending in the direction of feed, a work supporting horn actuated towards and from the apex of the angularly disposed surfaces on the work support, and a presser acting to clamp the moccasin pieces against said angularly disposed work engaging surfaces, of a divided tip on the presser, the parts of which are relatively movable, for enabling the presser to engage the moccasin pieces and to move the pieces separately towards the apex of the work support while clamping them.

6. In a machine for bringing together progressively the edges of the bevel edged top and vamp pieces of a moccasin type shoe upper and simultaneously inserting a permanent seam along the edges, the combination with stitch forming devices including a work penetrating instrument, a work support having fixed work engaging surfaces disposed at an angle with relation to each other and extending in the direction of feed to form an apex, a work supporting horn actuated towards and from the apex of the angularly disposed work engaging surfaces of the work support, and a presser acting to clamp the moccasin pieces against the angularly disposed surfaces of the work support, of a yielding tip on the presser having a work engaging surface roughened with elongated projections extending parallel to the line of feed for causing the presser tip to urge the moccasin piece engaged thereby towards the apex of the work support while clamping said piece.

7. In a machine for bringing together progressively the edges of the bevel edged top and vamp pieces of a moccasin type shoe upper and simultaneously inserting a permanent seam along the edges, the combination with stitch forming devices including a work penetrating instrument, a work support having work engaging surfaces disposed at an angle with relation to each other and extending in the direction of feed, a work supporting horn actuated towards and from the apex of the angularly disposed surfaces on the work support, and a presser acting to clamp the moccasin pieces against said angularly dis-

posed work engaging surfaces, of a divided tip on the presser, the parts of which are relatively movable, for enabling the presser to engage the moccasin pieces separately and to move towards the apex of the work support after clamping one of said pieces, and a centering gage for preventing one moccasin piece from displacing the edge of the other piece from the apex of the work support while being clamped.

8. In a machine for bringing together progressively the edges of the bevel edged top and vamp pieces of a moccasin type shoe upper and simultaneously inserting a permanent seam along the edges, the combination with stitch forming devices including a work penetrating instrument, a work support having work engaging surfaces disposed at an angle with relation to each other and extending in the direction of feed, a work supporting horn actuated towards and from the apex of the angularly disposed work engaging surfaces of the work support, of a divided tip having surfaces disposed at an angle to each other corresponding with the angle of the work engaging surfaces on the work support and comprising relatively movable sections, one of which is rigidly secured to the horn and the other of which is mounted to yield on the horn in the direction of movement of the horn towards and from the work support to cause the tip section secured rigidly to the horn to crowd the moccasin piece engaged thereby into the apex of the work support before the other of said moccasin pieces is clamped.

9. In a machine for bringing together progressively the edges of the bevel edged top and vamp pieces of a moccasin type shoe upper and simultaneously inserting a permanent seam along the edges, the combination with stitch forming devices including a work penetrating instrument, a work support having work engaging surfaces disposed at an angle with relation to each other and extending in the direction of feed and a presser acting on the pieces to crowd the edges into the apex formed by the angularly disposed work engaging surfaces of the work support with the bevel faces registering in the path of operation of the stitch forming devices, of a plate on the work support for supporting the top piece of the upper in flattened condition both at the edge and remote from the edge to cause all the flexure at the sewing point required in bringing the bevel faces into register to be taken up by the vamp of the assembled moccasin upper.

10. In a machine for bringing together progressively the edges of the bevel edged top and vamp pieces of a moccasin type shoe upper and simultaneously inserting a permanent seam along the edges, the combination with stitch forming devices including a work penetrating instrument, a work support having work engaging surfaces disposed at an angle with relation to each other and extending in the direction of feed and a presser acting on the pieces to crowd the edges into the apex formed by the angularly disposed work engaging surfaces of the work support with the bevel faces registering in the path of operation of the stitch forming devices, of a plate on the work support for supporting the top piece of the upper in flattened condition both at the edge and remote from the edge to cause all the flexure at the sewing point required in bringing the bevel faces into register to be taken up by the vamp of the assembled moccasin upper, and a tip on the presser constructed and actuated to crowd the vamp into the apex of the work sup-

port during each sewing cycle before the top piece is clamped.

11. In a machine for bringing together progressively the edges of the bevel edged top and vamp pieces of a moccasin type shoe upper and simultaneously inserting a permanent seam along the edges, the combination with stitch forming devices including a work penetrating instrument, a work support having work engaging surfaces disposed at an angle with relation to each other and extending in the direction of feed and a presser acting on the pieces to crowd the edges into the apex formed by the angularly disposed work engaging surfaces of the work support with the bevel faces registering in the path of operation of the stitch forming devices, of a plate on the work support for supporting the top piece of the upper in flattened condition both at the edge and remote from the edge to cause all the flexure at the sewing point required in bringing the bevel faces into register to be taken up by the vamp of the assembled moccasin upper, and a divided tip on the presser having a yielding section acting on the vamp and extending closer towards the adjacent surface on the work support before clamping the moccasin pieces than the other section to its adjacent work support surface to cause the edge of the vamp to be crowded into the apex of the work support before the top piece is clamped.

12. In a machine for bringing together progressively the edges of the bevel edged top and vamp pieces of a moccasin type shoe upper and simultaneously inserting a permanent seam along the edges, the combination with stitch forming devices including a work penetrating instrument, a work support having work engaging surfaces disposed at an angle with relation to each other and extending in the direction of feed and a presser acting on the pieces to crowd the edges into the apex formed by the angularly disposed work engaging surfaces of the work support with the bevel faces registering in the path of operation of the stitch forming devices, of a plate on the work support for supporting the top piece of the upper in flattened condition both at the edge and remote from the edge to cause all the flexure at the sewing point required in bringing the bevel faces into register to be taken up by the vamp of the assembled moccasin upper, and a tip on the presser acting on the moccasin top piece at a location with reference to the direction of work feed in advance only of the point of operation of the penetrating instrument to cause the presser while crowding the top piece into the apex of the work support to urge the edge of the top piece along that portion which is entering the notch of the work support more firmly towards the apex than the sewed portion of the top piece edge.

13. In a machine for bringing together progressively the edges of the bevel edged top and vamp pieces of a moccasin type shoe upper and simultaneously inserting a permanent seam along the edges, the combination with stitch forming devices including a work penetrating instrument, a work support having work engaging surfaces disposed at an angle with relation to each other and extending in the direction of feed and a presser acting on the pieces to crowd the edges into the apex formed by the angularly disposed work engaging surfaces of the work support with the bevel faces registering in the path of operation of the stitch forming devices, of a plate on the work support for supporting

the top piece of the upper in flattened condition both at the edge and remote from the edge to cause all the flexure at the sewing point required in bringing the bevel faces into register to be taken up by the vamp of the assembled moccasin upper, and a tip on the presser acting on the moccasin top piece at a location with reference to the direction of work feed in advance only of the point of operation of the penetrating instrument to cause the presser while crowding the top piece into the apex of the work support to urge the edge of the top piece along that portion which is entering the notch of the work support more firmly towards the apex than the sewed portion of the top piece edge and acting on the moccasin vamp along the seam line at both sides the point of operation of the penetrating instrument to crowd the vamp uniformly into the apex of the work support.

14. In a machine for bringing together progressively the edges of the bevel edged top and vamp pieces of a moccasin type shoe upper and simultaneously inserting a permanent seam along the edges, the combination with stitch forming devices including a work penetrating instrument, a work support having work engaging surfaces disposed at an angle with relation to each other and extending in the direction of feed and a presser acting on the pieces to crowd the edges into the apex formed by the angularly disposed work engaging surfaces of the work support with the bevel faces registering in the path of operation of the stitch forming devices, of a tip on the presser provided with a first surface having a raised portion acting on the top piece of the moccasin at a location along the seam line in advance only of the point of operation of the penetrating instrument and with a second surface at an angle to the first surface acting on the vamp of the moccasin along the seam line at both sides the point of operation of the penetrating instrument.

15. In a machine for bringing together progressively the edges of the bevel edged top and vamp pieces of a moccasin type shoe upper and simultaneously inserting a permanent seam along the edges, the combination with stitch forming devices including a work penetrating instrument, a work support having work engaging surfaces disposed at an angle with relation to each other and extending in the direction of feed and a presser acting on the pieces to crowd the edges into the apex formed by the angularly disposed work engaging surfaces of the work support with the bevel faces registering in the path of operation of the stitch forming devices, of a tip on the presser provided with a first surface having a raised portion acting on the top piece of the moccasin at a location along the seam line in advance only of the point of operation of the penetrating instrument and with a second surface at an angle to the first surface acting on the vamp of the moccasin along the seam line at both sides the point of operation of the penetrating instrument, and means for causing the second surface of the presser tip to engage the moccasin vamp before the first surface engages the top piece.

16. In a machine for sewing the top or tongue and side pieces for an unlasted moccasin shoe upper cut to be assembled with the outer surfaces diverging from each other and the surfaces along the edges disposed at an angle with relation to each other smaller than the angle more remote from the edges, the combination with stitch forming devices including a work penetrat-

ing instrument, a work support having work engaging surfaces disposed at an angle corresponding to that of the outer surfaces along the edges of the moccasin pieces, and a presser acting on the pieces to crowd the edges into the apex of the angularly disposed work engaging surfaces of the work support, of a centering fin on the work support opposite the point of operation of the work penetrating instrument extending in the direction of feed between the edges of the moccasin pieces opposite the operating point of the penetrating instrument with its exposed edge clear of the seam line.

17. In a machine for sewing the top or tongue and side pieces for an unlasted moccasin shoe upper cut to be assembled with the outer surfaces diverging from each other and the surfaces along the edges disposed at an angle with relation to each other smaller than the angle more remote from the edges, the combination with stitch forming devices including a work penetrating instrument, a work support having work engaging surfaces disposed at an angle corresponding to that of the outer surfaces along the edges of the moccasin pieces, and a presser acting on the pieces to crowd the edges into the apex of the angularly disposed work engaging surfaces of the work support, of a divided tip on the presser the parts of which are relatively movable for causing the presser to clamp the moccasin pieces separately, and mechanism for actuating the presser to urge the side piece within the apex of the angularly disposed surfaces of the work support before the top piece is clamped.

18. In a machine for sewing the top or tongue and side pieces for an unlasted moccasin shoe upper cut to be assembled with the outer surfaces diverging from each other and the surfaces along the edges disposed at an angle with relation to each other smaller than the angle more remote from the edges, the combination with stitch forming devices including a work penetrating instrument, a work support having work engaging surfaces disposed at an angle corresponding to that of the outer surfaces along the edges of the moccasin pieces, and a presser acting on the pieces to crowd the edges into the apex of the angularly disposed work engaging surfaces of the work support, of a tip on the presser provided with a first surface acting on the top piece of the moccasin and a second surface at an angle to the first surface acting on the side piece of the moccasin, and an adjustable pivot about which the presser is actuated towards and from the work support for changing the position of the presser at right angles to its path of actuation towards and from the work support to cause one of said presser tip surfaces to engage a work piece before the other.

19. The method of progressively assembling the top piece and vamp of a moccasin type shoe having their meeting edges beveled which comprises imparting a step-by-step feeding movement to the pieces lengthwise of their edges into positions determined by guiding means acting along the bevel surfaces of the pieces to bring the edges into register progressively, and separately clamping the pieces in each position while thus registered between successive feeding movements.

20. The method of progressively assembling and securing together the top piece and vamp of a moccasin type shoe having their uncemented meeting edges beveled which comprises imparting a step-by-step feeding movement to the pieces lengthwise of their edges into positions de-

terminated by guiding means acting along the bevel surfaces of the pieces to bring the edges into register progressively, separately clamping the pieces in each position while thus registered between successive feeding movements and sewing the pieces while clamped.

21. The method of uniting the edges of the top and vamp pieces for an unlasted moccasin shoe upper cut with a pattern to be assembled with the outer surfaces diverging from each other at an obtuse angle and formed with bevels on the meeting edges to cause the outer surfaces along the edges to assume an acute angular relationship when the faces of the bevels are brought into register including the steps of flexing the vamp along the edge from obtuse angular relationship with the top piece into acute angular relationship with the top piece while maintaining the top piece substantially in flattened condition to bring the bevel faces into register, fastening the flexed edge of the vamp to the flattened top piece, and thereafter releasing the fastened pieces to enable the flexure in the vamp to be transferred at least partially to the edge of the top piece.

22. The method of uniting the edges of the top and vamp pieces for an unlasted moccasin shoe upper cut with a pattern to be assembled with the outer surfaces diverging from each other at an obtuse angle and formed with bevels on the meeting edges to cause the outer surfaces along the edges to assume an acute angular relationship when the faces of the bevels are brought into register, including the steps of flexing the vamp along the edge from obtuse angular relationship with the top piece into acute angular relationship with the top piece while maintaining the top piece substantially in flattened condition to bring the bevel faces into register, sewing the flexed edge of the vamp to the flattened top piece with stitches passing through the registering bevel faces, and thereafter releasing the sewed pieces to enable the flexure in the vamp to be transferred, at least partially, to the edge of the top piece.

23. The method of uniting the edges of the top and vamp pieces for an unlasted moccasin shoe upper cut with a pattern to be assembled with the outer surfaces diverging from each other at an obtuse angle and formed with bevels on the meeting edges to cause the outer surfaces along the edges to assume an acute angular relationship when the faces of the bevels are brought into register, including the steps of flexing the vamp along the edge from obtuse angular relationship with the top piece into acute angular relation-

ship with the top piece while maintaining the top piece substantially in flattened condition to bring the bevel faces into register, sewing the flexed edge of the vamp to the flattened top piece with 5 stitches passing through the registering bevel faces, turning the flattened top piece within its own plane while sewing about the toe portion of the seam, and releasing the sewed pieces to enable the bent edge of the vamp to straighten and the flattened top piece to be bent along its edge by pressure of the bevel face on the vamp.

24. The method of uniting the edges of the top and vamp pieces for an unlasted moccasin shoe upper cut with a pattern to be assembled with the outer surfaces diverging from each other at an obtuse angle and formed with bevels on the meeting edges to cause the outer surfaces along the edges to assume an acute angular relationship when the faces of the bevels are brought into 10 register, including the steps of flexing the vamp progressively along the edge from obtuse angular relationship with the top piece into acute angular relationship with the top piece while maintaining the top piece in flattened condition to 15 bring the bevel faces on both pieces into register, sewing the flexed edge of the vamp to the flattened top piece as the bending operation progresses with stitches passing through the registering bevel faces, and releasing the sewed pieces 20 continuously, directly following the sewing operation, to enable at least a portion of the flexure in the vamp to be transferred progressively to the side piece.

25. In a machine for sewing the top or tongue 35 and side pieces for an unlasted moccasin shoe upper cut to be assembled with the outer surfaces diverging from each other and the surfaces along the edges disposed at an angle with relation to each other smaller than the angle more 40 remote from the edges, the combination with stitch forming devices including a work penetrating instrument, a work support having work engaging surfaces disposed at an angle corresponding to that of the outer surfaces along the 45 edges of the moccasin pieces, and a presser acting on the pieces to crowd the edges into the apex of the angularly disposed work engaging surfaces of the work support, of a centering fin 50 on the work support opposite the point of operation of the work penetrating instrument arranged to engage the pieces and to act with the work support in bringing the edges of the pieces progressively into register in the path of the 55 stitch forming devices.

FRED ASHWORTH.
